UNITED STATES PATENT OFFICE

GUSTAV NIEMANN, OF DUISBURG, GERMANY

CRANE

Application filed October 31, 1927, Serial No. 230,049, and in Germany April 28, 1927.

The jib crane of the invention differs from other cranes of its type by the simple manner in which the horizontal movement of the load and the balancing of the weight of the jib are attained. According to the invention, a simple guide member moving about an axis is employed, which guide member carries a load rope pulley and, if necessary, also the weight for balancing the weight of the jib. The pulley and the counter-weight thus move in a curved path about the pivotal point of the guide member. The guide member is supported at the upper end upon the jib which, for the purpose, is provided with a curved guiding or cam face; the end of the guide member travels along the guiding curved or cam face during the luffing movement, the curvature of the cam face being such that, by reason of the movement of the pulley, the load moves along an exactly horizontal plane and at the same time the weight of the jib is approximately or exactly balanced.

According to the invention, again, the movement of the pulley and of the counter-weight may be effected independently, that is to say, there may be provided a guide member and a curved guiding or cam face on the jib for the pulley, and a separate set of these elements for the counter-weight. The weight may be movable with respect to the guide member and finally the curved guiding or cam face may at the same time serve as a part of the luffing mechanism.

Several constructions of crane according to the invention are illustrated, by way of example, in the accompanying diagrammatic drawings.

Figure 1 is an elevation of a crane provided with a simple pivoted guide member.

Figure 2 is a side elevation of a crane provided with a counter-weight which is movable upon the guide member.

Figure 3 is a side elevation of a crane having two separate guide members.

Figures 4 and 4^a are side elevations of cranes provided with guide members which serve also to form part of the luffing gear.

The crane according to Figure 1 is provided with a revolving frame 1, upon which

is supported the jib 2, which moves about the axis 3. The curved guiding or cam face 5 is disposed at the rear end 4 of the jib.

Furthermore, the revolving frame is provided with a pivotal axis 8, about which the guide member 7 revolves. The latter is provided at its upper end with a pulley 10 for the load rope 11 and with a counter-weight 12, and it is guided by rollers 6 on the curved guiding or cam face 5 of the jib. The rope passes from the drum 13, over the pulley 10, thence to the pulley 2^a at the extreme end of the jib, and then vertically downwards to the load hook 11^a. If the jib 2 is luffed, the pulley 10 and the guide member 7 move from the position shown in dotted lines in the drawing into the position shown in full lines, and the load rope is slackened in such manner that the load moves on an exactly horizontal plane.

With such a luffing movement, the centre of gravity of the jib is raised, but at the same time the counter-weight 12 falls so that the luffing motor has little work to do, other than overcoming friction.

The neutralization of the tipping moment of the crane with reference to the plane A—B is assisted by the counter-weight since this approaches or recedes from the plane A—B at the same time as the jib, but remains always at the opposite side of the plane A—B to that occupied by the jib.

In Figure 1 the counter-weight is arranged on the axis of the rollers 6, the free end of the guide member resting upon the curved guiding or cam face 5. Such free end may, however, be disposed upon an extension of the guide member in front or to the rear of these rollers, as also at a distance from them laterally. The counter-weight 12 may be movably provided on the guide member 7, as shown in Figure 2. In this case it rests upon the slide or track 25 or the like, and is suspended from a rope retaining member 26, which is pivoted to the jib 2 at 28. The rope 26 or retaining member is guided over a pulley 27 fixed to the guide member 7. For the rest, the numerals indicated in Figure 1 apply also to Figure 2. It will be noted, however, that in this construc-

tion the load rope passes from the drum 13 first over a guide pulley on the pivotal axis 3 of the jib before passing around the pulley 10 and that the curved guiding or cam face 4 is of a somewhat different shape. Instead of the rope retaining member being fastened to the jib, it may be fastened to the fixed frame of the crane, for example, to the pivotal axis 3 of the jib. The track for the counter-weight on the guide member 7 may also be curved to any desired form in order to ensure that the counter-weight shall occupy the desired position with respect to the jib through the luffing movement.

If it be desired to secure the same exactness with the balancing of the weight as with the horizontal path taken by the load, it is advisable to employ two separate guide members as shown in Figure 3. The guide member 7 in this case carries only the pulley 10, and it is supported upon the curved guiding or cam face 5 as in the construction already referred to.

There is, however, still a further guide member 26, which is supported upon a second curved guiding or cam face 25 on the jib, and which in turn supports the counter-weight 12. The curved guiding or cam face 25 is so determined that the counter-weight falls, in every moment of time, through a distance corresponding to the lift of the jib. In this arrangement the opposing weights may be made to balance so exactly that there are no forces of reaction of the jib acting upon the luffing motor, because they can be kept smaller than the frictional forces of the jib system. In this way the jib movement is under complete control, and the motor may for example, be constructed, as is an ordinary main current motor, without the fear that its speed of rotation will vary considerably, as is the case when the balancing of weights is inexact.

In Figures 1, 2 and 3 the luffing mechanism has been omitted for the sake of clearness. It may, however, consist of a spindle drive, crank drive, or the like as is usual in luffing cranes.

The drive for the drawing-in mechanism itself is advantageously disposed in connection with the guiding curved or cam face on the jib in such manner that the curved or cam face, or the rear end of the jib is provided with a rack, into which engages a gear wheel on the guide member. Such a drive is illustrated in Figure 4, which for the rest shows the same crane as the figures of the drawings hereinbefore described.

The luffing motor 14 drives the vertical shaft 16 through a worm gear 15, and the gear wheel 17 is mounted on it at its upper end. It engages in a gear wheel 18 upon the axis of rotation 8 of the guide member 7, which in turn drives the gear

wheel 19 upon the shaft 20. This shaft is mounted on the guide member 7 and carries a gear wheel 21, which engages in a bevel gear wheel 22. The wheel 22 engages in a further gear wheel 23, which in turn engages in a rack 24 on the curved guiding or cam face 5. The guide member 7 is thus at the same time employed as a carrier for the luffing gear.

As will be seen from Figure 4^a, the luffing motor 14 may be provided on the guide member itself, in which construction it drives the spindle 20 direct. In the example illustrated this spindle, by means of the nut 28, at the same time moves the counter-weight 12, which moves relatively to the guide member in the manner required to attain the desired object. Instead of a curved guiding or cam face moved with the jib, a stationary cam, and, corresponding thereto, a guide member rotatable about an axis on the jib may be employed without departing from the invention.

I claim:

1. A jib crane provided with a simple jib and a movable pulley which is controlled by the jib and supports the load rope to ensure the load moving in a horizontal plane when the crane is luffed, comprising a supporting frame, a jib pivoted at its lower end to the supporting frame, a guiding surface of camlike form mounted upon the jib adjacent the lower end, a guide member pivoted to the supporting frame to the rear of the jib and carrying the movable pulley over which the load rope is led, the said guide member engaging the guiding surface of the jib.

2. A jib crane as set forth in claim 1, comprising rollers by which the guide member travels upon the guiding surface of the jib, the movable pulley being mounted upon the axis of the said rollers.

3. A jib crane as set forth in claim 1, comprising a counterweight which is moved by the guide member for the purpose of balancing the weight of the jib.

4. A jib crane according to claim 1, comprising rollers carried by the guide member and engaging the guiding surface of the jib, the movable pulley and a counterweight for balancing the weight of the jib being provided upon the axis of the rollers.

5. A jib crane according to claim 1, comprising a counterweight mounted upon the guide member, the said counterweight being movable with and upon the said guide members.

6. A jib crane according to claim 1, comprising a counter-weight movably carried by the guide member for balancing the weight of the jib, and a flexible member connecting the said counter-weight to the jib.

7. A jib crane according to claim 1, wherein a second guide member is provided to carry a counterweight for balancing the weight of the jib, and a second guiding surface is provided upon the jib for co-operating therewith.
